UNITED STATES PATENT OFFICE.

HERBERT L. CROUSE, OF WASHBURN, AND CARL M. JOHNSON, OF WOODLAND, MAINE.

BARK-REMOVING MACHINE.

Application filed March 14, 1921. Serial No. 451,987.

To all whom it may concern:

Be it known that we, HERBERT L. CROUSE and CARL M. JOHNSON, citizens of the United States, residing at Washburn and Woodland, respectively, in the counties of Aroostook and Washington and State of Maine, have invented certain new and useful Improvements in Bark-Removing Machines; and we do declare the following to be a full, clear, and exact description of the invention, such as will enable others skilled in the art to which it appertains to make and use the same.

Our invention relates to machines for removing bark from pulp wood and comprises briefly feeding means for the logs, a log rest co-operable with the feeding means in supporting the logs, and a bark removing cutter above the feeding means and log rest.

One object of the invention is to provide a novel arrangement of parts for simultaneously moving both the cutter and the log rest, toward or from the feeding means, according to the size of the logs, a single hand-control being employed for effecting the proper adjustment of said cutter and rest.

Other objects are to provide novel means for carrying and vertically adjusting the cutter head, to provide a unique type of rotatable gauge for controlling the depth of the cut taken by the cutter head, and to construct the cutter head in a simple and efficient manner to prevent any possibility of the blades digging into the log to an undesirable extent.

Still further objects are to provide a novel arrangement of parts for mounting the log feeding wheels, to provide unique lubricating means for the driving connections of said wheels, and to devise an efficient variable speed friction drive for said wheels.

With the foregoing and minor objects in view, the invention resides in the novel construction and arrangement of parts herein-after fully described and claimed, the descriptive matter being supplemented by the accompanying drawings.

Figure 1 is a side elevation of a bark removing machine constructed in accordance with our invention.

Figure 2 is a top plan view.

Figure 3 is a vertical longitudinal sectional view.

Figure 4 is a top plan view with parts 55 broken away and in horizontal section.

Figure 5 is a detail horizontal sectional view as indicated by line 5—5 of Fig. 6.

Figure 6 is a vertical transverse sectional view as indicated by line 6—6 of Fig. 1. 60

Figure 7 is a transverse sectional view as designated by line 7—7 of Fig. 1.

Figure 8 is a top plan view of the rotary cutter and its carrying frame.

Figure 9 is a detail vertical sectional view 65 through one of the feed wheels and associated parts.

Figure 10 is a detail vertical sectional view as indicated by line 10—10 of Fig. 1, showing more particularly parts of the 70 variable speed driving mechanism for the feeding wheels.

Figure 11 is a side elevation of the rolling gauge wheel.

Figure 12 is a vertical sectional view 75 thereof as indicated by line 12—12 of Fig. 11.

Figure 13 is a side elevation of the rotary cutter head.

Figure 14 is a longitudinal sectional view 80 of the cutter head, as indicated by line 14—14 of Fig. 15.

Figure 15 is a vertical transverse section as indicated by line 15—15 of Fig. 13.

Figure 16 is a plan view of one of the 85 cutter blades.

In the drawings above briefly described, the numeral 1 designates a horizontally elongated frame preferably constructed of angle iron and mounted on skids 2. These skids 90 however may well rest on appropriate chocks 3 when the machine is set up for use, so as to prevent rotting. On the rear end of the frame 1, the main drive shaft 4 is mounted, said shaft being positioned transversely of 95 the frame and having a pulley 5 to engage a driving belt not shown. The front end of the frame is of greater width than the rear end thereof and is provided with upper and lower sets of short longitudinal bars 6 and 100 7 respectively. As shown most clearly in Figs. 4 and 6, a plurality of horizontal plates 8 are supported by the upper bars 6, one edge of said plates being pivoted to the bars 6 by means of vertical shafts 9 which rise 105 through said bars and plates, as shown in the figures referred to and also well illustrated in Fig. 9. The free edges of the sev-

eral plates 8 overlap the pivoted edges of the adjacent plates so that a shield is formed to prevent pieces of bark and wood from interfering with the driving gearing below the plates. Each plate 8 is provided with an opening 10 and a plurality of toothed log feeding wheels 11 are rotatably supported in the several openings upon appropriate shafts 12, one side of said wheels 11 being provided with gear teeth 13 meshing with horizontal bevel gears 14 which are bolted to similar gears 15 rotatable upon the lower ends of the shafts 9 (see Fig. 9). The gears 15 mesh with bevel gears 16 on a transverse horizontal shaft 17 mounted in bearings 18 which are secured to the bars 7, said shafts 17 being rotated by the means yet to be described.

In addition to carrying the shafts 17, it will be seen that the bearings 18 also rigidly support the vertical shafts 9, and we prefer that these shafts 9 shall be of the tubular form shown in Fig. 9 to contain oil for the purpose of lubricating the gears 15 and the bearings 18, suitable oil holes 19 and 20 being provided for this purpose.

It will be seen that the gearing above described will drive the log feeding wheels 11 and by mounting these wheels on the plates 8 and making provision for turning these plates upon their pivots, the angular relation of said wheels with respect to the logs, may be varied, whereby to cause either slow or rapid feeding, while at the same time rotating the log. For swinging the plates 8 upon their pivots and holding them in adjusted position, we preferably connect said plates by a bar 21 shown most clearly in Fig. 4, one end of said bar being connected at 22 with a suitable hand lever 23 which may well be locked in adjusted position by an appropriate rack 24. It will be observed that regardless of the extent to which the several plates are swung, they still form an effective shield to prevent any undesirable amount of bark and the like from falling onto the subjacent driving gearing for the wheels 11.

Slightly in rear of and above the feed wheels 11, is a log rest which preferably comprises a transverse shaft 25 and appropriate log supporting rollers 26 mounted thereon, said shaft being rotatably mounted in bearings 27 which rise from longitudinally disposed slide bars 28, these bars being slidably mounted on tracks 29 which are supported by appropriate spacers 30 from the uppermost of the longitudinal bars 31 of the frame 1. The slide bars 28 are provided with racks 32 meshing with pinions 33 on a transverse shaft 34 mounted in bearings on the side bars 31. A lever 35 and ratchet mechanism 36 is employed for turning shaft 34 as required and an appropriate dog 37 is shown for holding said shaft

against retrograde movement. It will be seen that rotation of the shaft 34 will cause its pinions 33 and the rack bars 32 to move the slide bars 28 so as to shift the rollers 26 toward or from the feed wheels 11, according to the size of the log from which bark is being removed. Rotation of the shaft in question, also vertically adjusts a supplemental frame 38 which carries the bark removing cutter 39.

Frame 38 is disposed above the main frame 1 and at its rear end is loosely pivoted at 40 to posts 41 which rise from a transverse bar 42 of said frame 1, said frame 38 being also connected with the main frame 1 by appropriate brace rods 43 which diverge rearwardly as shown in Fig. 2 and thus prevent any appreciable lateral motion of said frame 38. The frame in question, however is permitted slight lateral tilting so that the cutter 39 may oscillate to a slight extent according to irregularities in the logs.

Near its front end, frame 38 is provided with a pair of laterally extending guide arms 44 through which the reduced upper ends 45 of a pair of vertical rack bars 46 extend slidably. These rack bars are in mesh with gears 47 on the shaft 34 and it will be seen that rotation of this shaft will therefore raise or lower the bars 46 to vertically adjust the cutter carrying frame 38. The two bars 46 are rigidly connected by a transverse bar 48 (see Fig. 7) and a coil spring 49 is interposed between said bar 48 and a guide 50 carried by the frame 38, a vertical pin or the like 51 being preferably passed through the spring, the guide 50 and the bar 48 so as to properly hold the several parts in their relative positions. The spring 49 supports the weight of the frame 38 and cutter 39 upon the bar 48 which is in turn supported by the vertical rack bars 46 and this weight has a tendency to rotate the shaft 34 in one direction. Such rotation however is prevented by the dog 37 as will be clear by referring to Fig. 1.

The rotary cutter 39 is mounted on a shaft 52 carried by the front end of the frame 38, said shaft being parallel to the shaft 25 and being driven by appropriate belts 53 from pulleys 54 on the main drive shaft 4. The cutter is housed in an appropriate casing 55 and between this casing and one side of the frame 38, we mount a ring-like gauge wheel 56. The hub 57 of the wheel 56 loosely surrounds the shaft 52 of the cutter 39 and the wheel is mounted so that it may swing laterally after the fashion of a caster wheel, so as to truly roll upon the logs instead of dragging thereon. We prefer to mount the wheel 56 on a swinging arm which consists of parallel side plates 58 shown most clearly in Figs. 11 and 12, the inner ends of said plates being provided with upstanding pivot

pins 59 which are rotatably and slidably received in guides 60 on a post 61 rising from frame 38. A hand lever 62 is fulcrumed to the post 61 and has its front end 5 received between lugs 63 which extend from the inner end of the wheel carrying arm, an appropriate rack 64 being employed for holding said lever in adjusted position. By the arrangement of parts described, the 10 wheel 56 may be vertically adjusted by properly operating the lever 62 and as said wheel travels on the logs as they are fed through the machine, it regulates the depth which the cutter 39 is allowed to cut. In the present showing, the gauge wheel operates in connection with a fixed gauge bar 65 which is located at the end of the cutter 9 remote from said wheel. This gauge bar as shown for instance in Fig. 6, slides on the logs 15 after the bark has been removed therefrom, but the wheel 56 travels on the bark. This wheel may swing laterally when encountering knots or the like and since the log is both rotated and longitudinally fed, said 20 wheel will at most times assume an oblique position so as to roll freely.

While it will be appreciated that any form of rotary cutter 39 may be employed, we prefer that the construction detailed in Figs. 13 30 to 16 shall be used. In these figures, the numeral 66 designates a hollow flat-sided head having internal integral hubs 67 keyed on the shaft 52. At longitudinally spaced points, the head 66 is provided with circumferentially extending flanges 68 whose outer edges are of circular form, being provided with notches 69 co-incident with two opposed flat sides of the head 66. These notches receive a pair of cutting blades 70 35 which are notched at 71 to receive the portions of the flanges 68 at the inner ends of the notches 69, said blades being additionally notched at 72 for the reception of bolts 73 by means of which they are clamped 40 against the opposed flat sides of the head 66. The cutting edges of the blades 70 extend slightly beyond the flanges 68 and while these flanges are notched in front of said cutting edges as seen at 74, they will prevent 45 them from digging an excessive distance into the logs.

Heretofore, we have referred to driving means for the shaft 17 and while this means might assume any adequate form, we prefer 55 to employ the construction shown. A gear 74 is secured on this shaft and meshes with a pinion 75 on a transverse shaft 76 which is supported in appropriate bearings on certain of the bars 7. Shaft 76 is provided with 60 a bevel gear 77 meshing with a pinion 78 on a longitudinal shaft 79 which is located at one side of the frame 1 and held rotatably by appropriate bearings 80. On shaft 79, is a 65 slideable friction wheel 81 whose periphery contacts with the flat driving surface of an other friction wheel 82 on a transverse shaft 83 which is driven by a belt 84 and pulleys 85 from the main drive shaft 4. A suitable thrust bearing 86 and a lever 87 are provided for crowding the friction wheel 82 against 70 the wheel 81 when the latter is moved from its idle position at the center of said wheel 82. We have shown the lever 87 connected by a link 88 and thumb screw 89, with a vertical hand lever 90 which is appropriately connected by a rod or the like 91 with the hub of the sliding wheel 81. When this wheel 81 is at the center of the wheel 82 and is consequently idle, the link 88 is parallel 75 with the shaft 83, as shown for instance in Fig. 4 and hence the wheel 82 is not in driving contact with the wheel 81. When lever 90 however is swung to shift the wheel 81 towards the periphery of wheel 82, angling of the link 88 causes it to pull upon the lever 87 thus crowding the wheel 82 into tight driving contact with the wheel 81. Whenever necessary, the thumb screw 89 may be operated to relatively adjust the levers 87 and 90 and a suitable rack 92 may be employed for said lever 90, the link 88 and thumb nut 89 serving to hold said lever in engagement with the rack as will be clear from Fig. 4.

We prefer to drive the shaft 25 and the 95 rollers 26 from the shaft 76 and for this purpose, we have shown sprocket chains 93 and sprockets 94, certain of these sprockets being mounted at the juncture of two pivotally connected arms 95 whose outer ends are 100 pivoted on the shafts 25 and 76. These arms serve to properly space the sprocket wheels and keep the chains 93 tight, regardless of the amount which shaft 25 is shifted toward and from the feed wheels 11.

In operating the machine, lever 35 is operated to elevate the frame 38 of cutter 39 according to the size of the log from which bark is to be removed. Raising of this frame and cutter simultaneously moves the log supporting rollers 26 rearwardly from the feeding wheels 11 and the log may then be placed in proper position upon said wheels and rollers. The frame 38 is now allowed to lower by gravity, by releasing dog 37, 115 until the rotary cutter 39 acts on the log as it is fed through the machine by the wheels 11. As frame 38 lowers, the rollers 26 move forwardly into proper operative engagement with the log. The wheels 11 co-operate with the rollers 26 in rotating the log while feeding the same longitudinally so that the cutter 39 will remove the bark entirely around the log. Whenever necessary, the gauge wheel 56 may be raised or 120 lowered to regulate the depth of cut. In actual use, the machine has proven not only very rapid, but otherwise efficient and in every way desirable, for which reasons, the general construction shown and described, 125 130

is preferably followed. We wish it understood however that within the scope of the invention as claimed, the machine may be embodied in numerous forms other than that 5 herein disclosed.

We claim:

1. In combination, a frame, a horizontal row of log feeding wheels mounted thereon, a horizontal rotatable log rest on the frame 10 parallel with said row of feeding wheels for holding the logs against said wheels, said log rest being adjustable toward and from said wheels, a bark removing cutter above said wheels mounted for adjustment toward and 15 from the frame, and means for synchronizing the adjustments of said log rest and cutter, including means for permitting movement of said cutter independently of said log rest.
2. Arossing machine comprising a frame, a horizontal row of log feeding wheels thereon, a horizontal rotatable log rest parallel with said row of feeding wheels for holding the logs against said wheels, a horizontally movable carrier for said log rest 25 mounted on said frame, a bark removing cutter above said feeding wheels, a vertically movable carrier for said cutter mounted on said frame, rack bars connected with said carriers respectively, gearing mounted on the frame in mesh with said rack bars for insuring simultaneous movement of the two carriers, and means for rotating said gearing to raise the cutter carrier and to simultaneously adjust the other carrier, said means being releasable to permit said cutter carrier to descend by gravity and thereby adjust the other carrier simultaneously.
3. Arossing machine comprising a frame, 40 log feeding wheels mounted on said frame, a log rest adjacent said wheels, a bark removing cutter above said wheels, movable carriers for said rests and cutter, and connecting means between the two carriers for simultaneously adjusting them and synchronizing their movements and for permitting free movement of the cutter carrier independently of the other carrier.
4. Arossing machine comprising a frame, 45 a horizontal row of log feeding wheels thereon, a horizontal rotatable log rest parallel with said row of feeding wheels for holding the logs against said wheels, a horizontally movable carrier for said log rest 55 mounted on said frame, a bark removing cutter above said feeding wheels, a vertically movable carrier for said cutter mounted on said frame, rack bars connected with said carriers respectively, and gearing mounted on the frame in mesh with said rack bars for simultaneously adjusting both carriers and synchronizing their movements, the rack bar of the cutter carrier being slidably connected with this carrier to permit

vertical movement thereof independently of 65 the other carrier.

5. In combination, a frame, log supporting and feeding means thereon, a bark removing cutter above said supporting and feeding means, a vertically movable carrier for said 70 cutter mounted on said frame, a vertical adjusting bar for said carrier and means for operating said bar, said carrier having a guide through which the upper end of said bar passes slidably, and means yieldably 75 supporting said carrier on said bar.

6. In combination, a frame, log supporting and feeding means thereon, a bark removing cutter above said supporting and feeding means, a vertically movable carrier 80 for said cutter mounted on said frame, said carrier having a pair of guides, spaced adjusting bars whose upper ends pass slidably through said guides, a horizontal bar connecting said adjusting bars, spring means 85 supporting said carrier from said horizontal bar, and means for operating said adjusting bars to raise and lower said carrier.

7. A bark removing machine comprising a frame, bark removing means thereon, a gang of log feeding wheels, a plurality of plates pivotally mounted on said frame and having openings in which said wheels are mounted, driving means for said wheels below said plates, the latter being disposed in 90 overlapping relation and forming a shield for said driving means, and means for holding said plates when adjusted on their pivots to vary the angle of the wheels with respect 95 to the logs.

8. A bark removing machine comprising a frame, log feeding and guiding means on said frame, a rotary driven cutter above said feeding and guiding means, a vertically movable carrier for said cutter mounted on 105 said frame, and a gauge wheel for said cutter pivotally mounted on said frame on a vertical axis and adapted to roll on the logs, said wheel being free to swing horizontally to different angles.

9. A bark removing machine comprising a frame, log feeding and guiding means on said frame, a rotary driven cutter above said feeding and guiding means, a vertically movable carrier for said cutter mounted on 115 said frame, and a ring-like gauge wheel for said cutter surrounding the drive shaft thereof and mounted on said carrier to move to positions oblique to the logs.

10. A bark removing machine comprising a frame, log feeding and guiding means on said frame, a rotary driven cutter above said feeding and guiding means, a vertically movable carrier for said cutter mounted on 120 said frame, a ring-like gauge wheel for said cutter surrounding the drive shaft thereof, a carrying arm for said wheel comprising spaced side plates between which 125

said wheel is mounted, and means pivotally mounting said arm on said carrier for lateral swinging.

11. A bark removing machine comprising a frame, log feeding and guiding means on said frame, a rotary driven cutter above said feeding and guiding means, a vertically movable carrier for said cutter mounted on said frame, a gauge wheel for said cutter adapted to travel on the logs, an

arm carrying said gauge wheel, means mounting said arm on said carrier for free horizontal swinging and for vertical adjustment, and means for holding said arm in vertically adjusted position.

15

In testimony whereof we have hereunto set our hands.

HERBERT L. CROUSE.
CARL M. JOHNSON.
